UNITED STATES PATENT OFFICE.

WALTER M. CUSICK, OF BOSTON, MASSACHUSETTS.

INTERNAL-COMBUSTION ENGINE.

1,149,312.

Specification of Letters Patent.

Patented June 8, 1915.

Application filed October 24, 1912. Serial No. 727,483.

To all whom it may concern:

Be it known that I, WALTER M. CUSICK, a citizen of the United States, residing in Boston, county of Suffolk, and State of Massachusetts, have invented an Improvement in Internal-Combustion Engines, of which the following description, in connection with the accompanying drawings, is a specification, like letters on the drawings representing like parts.

This invention relates to an internal combustion engine or motor and is herein shown as embodied in a motor of the four cycle type.

The invention has for its object to provide an internal combustion engine or motor which is of increased efficiency, economical in construction and maintenance, easily accessible and silent in operation. To this end I employ hollow rotary inlet and exhaust valves, which are mounted to rotate in casings integral with the cylinders of the engine or motor and provided with water jackets which form part of the water jackets 25 of said cylinders. Provision is made for causing the cooler water to circulate through the jacket of the exhaust valve before it enters the jacket of the inlet valve for a purpose as will be described. Provision is also made for obtaining an even or uniform supply of fresh gas for each cylinder and provision is also made for preventing leakage of the gas between the cylinders through the valve casings as will be described. These 35 and other features of this invention will be pointed out in the claims at the end of this specification.

Figure 1 is a plan view of a four cylinder four cycle engine embodying this invention. Fig. 2, a front elevation of the engine shown in Fig. 1. Fig. 3, an end elevation showing one method of rotating the hollow valves. Fig. 4, a detail in cross section taken on the line 4—4 Fig. 1. Fig. 5, a detail in longitudinal section of the inlet valve, and Fig. 45 6, a detail to be referred to.

In the present instance the motor is provided with four cylinders, *a*, *b*, *c*, *d*, which are indicated by dotted lines in Fig. 1 and 50 are cast in pairs. Each cylinder is provided

with the usual piston *e* and rod *f* by which the piston is connected with the crank shaft *g*, having bearings in the crank case *h*. Each cylinder is provided at its upper end with ports 10, 12 in its head, with which co- 55 operate hollow rotary inlet and exhaust valves 13, 14, which are made in the form of cylinders or sleeves, mounted to rotate in cylindrical valve casings 15, 16, cast integral with each pair of cylinders. 60

The valve casings 15, 16 of one pair of cylinders as *a*, *b*, are arranged in line with the valve casings of the other pair of cylinders *c*, *d*, and are connected therewith gas tight by intermediate casings 19, 20, which 65 are readily detachable from the valve casings attached to the pairs of cylinders for purpose of assembling and for gaining access to the valves in case of repairs. The intermediate casings 19, 20 are of like construction and therefore only one need be described in detail.

Referring to Fig. 5, the intermediate casing 19, is shown as provided at its ends with hubs 22, which form bearings for the rotary 75 valve 13 and are externally threaded to be engaged by nuts or threaded sleeves 23, provided with end disks 24, which are removably secured by screws 25 to said nuts. The end disks 24 are designed to engage annular 80 flanges 26 on the valve casings 15, and gas tight joints between the hubs 22 and the flanges 26 are effected by washers 27 of suitable material.

The portion of the intermediate casing 85 19 between the hubs 22 is of larger diameter than the rotary valve 13, to form an annular chamber 30 with which communicates a gas inlet pipe 31, which is connected with the carburetor or other source of supply not 90 shown.

The rotary valve 13 within the intermediate casing 19 is provided with an opening 32, which is preferably covered by wire gage or other foraminous screen 33 to arrest dirt, 95 etc., and if desired a like screen 34 may be interposed between the gas inlet pipe 35 and the mouth 36 of the casing 19. The valve casings 20 for the exhaust rotary valve are connected in a similar manner by an inter- 100

mediate casing 40, with which is connected an exhaust pipe 41.

The hollow rotary inlet valve 13 consists of a sleeve having a port 42 for each cylinder, which ports are arranged to register with the gas inlet ports 10 for said cylinders, and the exhaust hollow rotary valve 14 is provided with like ports 43, which are arranged to register with the exhaust ports 12 of said cylinders.

The hollow rotary valves 13, 14 are provided with means for rendering them gas tight in their casings at a plurality of points in the length of said valves, so that gas under compression in one cylinder may not leak between the rotary valves and their casings into other cylinders or into the exhaust, which results may be accomplished as herein shown by providing said valves with a plurality of pairs of split packing rings 45, which are arranged so that their split ends break joints as shown in Fig. 5.

The rotary valves may be mounted at their ends upon ball bearings 46 in a manner well understood, and are closed at their ends and provided at one end with stud shafts 47, 48, which extend through removable end walls or caps 49 for the valve casings, and are operatively connected with the crank shaft to be driven thereby so as to make one revolution to every two revolutions of the crank shaft. In the present instance, the shafts 47, 48 are provided with sprocket wheels 50, 51 which are joined by a link chain 52 to a sprocket wheel 53 on the crank shaft. The caps 49 may be screwed upon the valve casings as represented in Fig. 6.

By making the intermediate sections detachable from the valve casings, the cylinders can be cast in pairs and the valves quickly and easily assembled. Furthermore the valve casings of each pair of cylinders may be provided with water jackets 55, 56, which are cast in one piece with the water jacket 57 of the cylinders, and the jackets of the valve casings are connected together between them by a jacket 58 for the heads of the cylinders.

50 The water jacket for the cylinders is provided with a water inlet 60, which is located on the exhaust side of the cylinders, and the water jacket for the gas inlet valve 13 is provided with a water outlet 61, which is located on the opposite side of the cylinders.

The cool water is first admitted into the jacket 57 of the cylinders and flows through the jacket 56 of the exhaust valve and 60 greatly reduces the temperature and pressure of the exhaust gases, and the water thus heated flows through the jacket 58 and the jacket 57 of the inlet valve, and increases the pressure and temperature of the

explosive mixture or fresh gas. Both of these results are beneficial to the motor and greatly increase the efficiency of the same and also serve to enable the motor to be run economically.

It will be observed that the gas supply pipe 35 is connected to the intermediate section 19 between the two pairs of cylinders, and as a result, the gas is supplied evenly to the cylinders of each pair. The opening in the exhaust valve may and preferably will not be provided with a screen.

Claims.

1. In a motor of the character described, in combination, a plurality of cylinders cast in pairs, and provided with separate inlet and exhaust ports in the head of each cylinder, cylindrical casings for inlet and exhaust valves integral with the cylinders of each pair, and arranged with the inlet valve casings in alinement with each other and with the exhaust valve casings in alinement with each other, hollow intermediate sections joining said alined inlet valve casings and said alined exhaust valve casings and detachable therefrom, means for securing said sections to the valve casings with which they coöperate, hollow rotary valves located in said casings and provided with ports coöperating with the ports in said cylinders, and means for rotating said valves. 95

2. In a motor of the character described, in combination, a plurality of cylinders cast in pairs, and provided with separate inlet and exhaust ports in the head of each cylinder, cylindrical casings for inlet and exhaust valves integral with the cylinders of each pair, and arranged with the inlet valve casings in alinement with each other and with the exhaust valve casings in alinement with each other, hollow intermediate sections joining said alined inlet valve casings and said alined exhaust valve casings and detachable therefrom, means for securing said sections to the valve casings with which they coöperate, hollow rotary valves located in said casings and provided with ports coöperating with the ports in said cylinders, means between said ports to prevent the escape of gas between the rotary valves and their casings, and means for rotating said valves, substantially as described. 105

3. In a motor of the character described, in combination, a plurality of cylinders arranged side by side but separate from each other and each provided with a port in its head, a cylindrical valve casing on each cylinder communicating therewith, a section of a valve casing located between said cylinders and detachably secured to the valve casings on said cylinders, a hollow rotary valve extended through said intermediate section into the valve casings on said cylinders, and provided with a port 120

which connects the intermediate section with the interior of the hollow valve and with additional ports to establish communication between the interior of said valve and

5 said cylinders, substantially as described.

In testimony whereof, I have signed my

name to this specification in the presence of two subscribing witnesses.

WALTER M. CUSICK.
